(57) **CLAIM**

The ornamental design for a linear motion push-up bar, as shown.

DESCRIPTION

FIG. 1 is a side perspective view of the linear motion push-up bar of the present invention;

FIG. 2 is a front view of the linear motion push-up bar shown in FIG. 1;

FIG. 3 is a top view of the linear motion push-up bar shown in FIG. 1; and,

FIG. 4 is a side view of the linear motion push-up bar shown in FIG. 1.
